CLAIM

The ornamental design for a composite seal, as shown and described.

DESCRIPTION

FIG. 1 is a front view of a composite seal in accordance with Embodiment 1 of the present design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a perspective view thereof;
FIG. 8 is a cross sectional view taken along line 8-8 of FIG. 5;
FIG. 9 is an enlarged view of the portion 9-9 of FIG. 8;
FIG. 10 is a front view of a composite seal in accordance with Embodiment 2 of the present design;
FIG. 11 is a rear view thereof;
FIG. 12 is a right side view thereof;
FIG. 13 is a left side view thereof;
FIG. 14 is a top view thereof;
FIG. 15 is a bottom view thereof;
FIG. 16 is a perspective view thereof;
FIG. 17 is a cross sectional view taken along line 17-17 of FIG. 14; and,
FIG. 18 is an enlarged view of the portion 18-18 of FIG. 17.
